LIFT FOR BUNDLE CARRIERS

Gustav Krueger, Lisbon, N. Dak.

Application October 19, 1942, Serial No. 462,660

1 Claim. (Cl. 56—480)

This invention relates to improvements in means for lifting the bundle carriers of tractor binders and more especially binders of the "Deere" type. These carriers have been provided with lifting means but the means are so constructed that, when the carrier has been raised to the upper limit of its movement, it has been supported in the path of portions of the packer mechanism with the result that a pounding action has been set up which has soon worn down or broken some of the parts and necessitated replacements.

The present invention has for its object to provide a lifting means so shaped and proportioned as not to interfere with the operation of a packer when the bundle carrier is in raised position, it being possible to accurately adjust the parts to insure free operation without interference.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings the preferred form of the invention has been shown.

In said drawings

Figure 1 is a side elevation of that portion of the bundle carrier lifting means constituting the present invention, its relation to one of the packers when the carrier is raised its maximum distance, being indicated.

Figure 2 is a plan view of some of the structure shown in Fig. 1.

Figure 3 is a front elevation of the parts constituting the present invention, other parts adjacent thereto being shown partly in section and partly in elevation.

Figure 4 is an enlarged section through the bundle carrier stop.

Figure 5 is a similar view showing a modified construction of the stop.

Referring to the figures by characters of reference, 1 and 2 designate superposed side portions of the binder, the upper member 2 having one or more hangers 3 suspended therefrom and supporting packers one of which has been indicated at 4. These packers are adapted to be actuated by a crank shaft 5 driven by a suitable mechanism provided for that purpose, the cranks being connected to the packers in the usual way

and operated by the usual or any preferred mechanism.

The parts thus far described are not in themselves a part of the present invention but can be found in a binder of the type heretofore mentioned. In the said binder the bundle carrier, which has been shown in part at 6 in the accompanying drawings is carried by a shaft 7 having a crank 8 at one end which is mounted for back and forth rotation in the tubular portion 9 of a casting which is fixedly joined to the member 1 and has an upstanding portion 10 reinforced by means of braces 11 and 12.

Shaft 7, which is comparatively short, is extended into and constitutes a bearing for one end of a tubular shaft 13 forming a part of the bundle carrier 6 and fixedly secured on that end of the tubular shaft 13 nearest the crank 8 is a collar 14 having an integral saddle 15 extending forwardly therefrom and laterally so as to pass beneath and transversely of the crank 8. This saddle is formed with a stop for limiting the relative movement of the crank and saddle. As shown in Figs. 2, 3 and 4, the stop can be in the form of a screw 16 provided with a lock nut 17 but, under certain conditions, it would be more advisable to provide a stop block 18 on the saddle which is welded thereto as shown in Fig. 5.

Back of the saddle 15 the sleeve 14 is formed with a lateral extension 19 which embraces the rear portion of the crank and has an upwardly extending ear 20 formed with an opening 21. This opening is adapted to receive the hooked lower end 21' of a connecting link 22 the upper end of which is screw-threaded as shown at 23 and is extended through an eye 24 at one end of a pin 25. Nuts 26 engage the screw-threaded portion 23 of link 22 and are positioned above and below the eye 24 so as to hold these parts assembled adjustably.

Pin 25 is extended transversely through the rearwardly extended arm 27 of a lifting crank 28 which, as shown particularly in Fig. 1, is substantially Y-shaped with a downwardly and forwardly extended arm 29 and an upwardly and forwardly extended arm 30. The lower end of arm 29 is extended into the casting 10 and pivotally connected thereto by a pin 31 while the upper end of arm 30 is pivotally engaged by a connecting rod 32 adapted to be actuated for the purpose of raising or lowering the bundle carrier.

An important feature of the present invention resides in the fact that the parts 22 and 28 are so proportioned and located that they will

not move into the path of the packer 4 when the bundle carrier is in either raised or lowered position. In other words when the crank arm 27 is swung upwardly by a pull through rod 32, it will actuate link 22 to pull upwardly on the collar 14 until the stop carried by saddle 15 comes against the crank 8 in the path thereof.

When the crank 28 reaches the upper limit of its movement which is determined by its contact with the casting 10 in which it is mounted, the arm 27 of the crank is below the path of the packer 4 and its hanger 3 but, because of the comparatively short length of the link 22 and the provision of the stop on the saddle 15, the carrier, when lifted by this movement of crank 28 will be properly elevated to support and carry the bundle. When it is desired to dump the carrier, the operation is reversed, motion being transmitted from rod 32 to arm 30 so as to permit downward movement of arm 27 or else the rod 32 can be released and the arm 27 can swing downwardly under the weight of the load subjected to it. This swinging action will of course allow the crank 8 to swing downwardly, thereby lowering the carrier and at the same time permitting the carrier to tilt downwardly and backwardly to release its load. This movement will not be sufficient to bring the arm 30 into the path of the hanger 3 and the packer 4.

As has heretofore been pointed out, when a carrier has been raised by means of the mechanism provided for that purpose, the member which is being displaced by the crank 28, has been brought into the path of one of the packers with the result that a pounding has been set up

which has interfered with the efficiency of the machine and has caused it to wear or break. It has been found that by shortening the link 22 and providing a stop on the saddle 15 whereby the extent of movement can be controlled, the objectionable features heretofore present and herein referred to are completely eliminated.

What is claimed is:

The combination with a binder, a crank 10 mounted to swing on one side portion thereof and extended laterally therefrom, a laterally extended shaft movable with the crank and a packer 15 mounted for lateral movement transversely of and above the crank, of a carrier including a tubular member rotatably mounted on said shaft, a collar rotatable with the tubular member, a saddle extending from the collar and under the crank, an adjustable stop on the saddle for engagement with the crank to limit the relative 20 movement of the crank and saddle, a substantially Y-shaped member having forwardly extended upper and lower arms and a rearwardly extended arm, said lower arm being pivotally mounted on the binder, operating means connected to the upper arm, the rearwardly extended arm being positioned at all times below the path of movement of the packer, and an adjustable link connection between the rearwardly extended arm and the collar, said link connection including a threaded member having a hook engaging a portion of the collar, a swivel pin 25 mounted in the rearwardly extended arm, said pin having an eye, and means on the threaded member for holding it adjustably to the eye.

GUSTAV KRUEGER.
